UNITED STATES PATENT OFFICE.

WILLIAM H. FAUBER, OF CHICAGO, ILLINOIS.

VELOCIPED.

SPECIFICATION forming part of Letters Patent No. 624,635, dated May 9, 1899.

Application filed February 12, 1896. Serial No. 579,000. (No model.)

To all whom it may concern:

Be it known that I, WILLIAM H. FAUBER, of Chicago, in the county of Cook and State of Illinois, have invented certain new and useful Improvements in Velocipedes; and I do hereby declare that the following is a full, clear, and exact description thereof, reference being had to the accompanying drawings, and to the letters of reference marked thereon, which form a part of this specification.

This invention relates to improvements in crank-shafts for velocipedes, and more particularly to an improved form of connection between the crank-shaft and the sprocket-wheel carried thereby.

The invention consists in the matters hereinafter described, and more particularly pointed out in the appended claims, and it will be more readily understood by reference to the accompanying drawings, in which—

Figure 1 is an end elevation of a crank-shaft and sprocket-wheel mounted thereon embodying one form of my invention. Fig. 2 is a view in side elevation of the crank-shaft shown in Fig. 1, together with the sprocket-wheel and connecting-arm thereof, which latter are shown in central section. Fig. 3 is a side elevation of the crank-shaft with the sprocket-wheel and bearing-ring removed. Fig. 4 is an inner face view of a slightly-modified form of the sprocket-wheel.

The invention is herein shown as applied to a crank-shaft having crank-arms made integral therewith and substantially like the crank-shaft set forth in a pending application filed by me November 18, 1895, Serial No. 569,316; but it is to be understood that the invention is capable of application to other forms of crank-shafts and that both of the crank-arms need not necessarily be made integral with the shaft.

Referring to said drawings, A designates as a whole the crank-shaft, comprising the shaft proper, A', and the crank-arms A² A³, shown in this instance as integrally united with the shaft A' at opposite ends thereof. The shaft A' is provided with two screw-threaded parts a a', adapted to afford attachment thereto of bearing rings or cones of ball-

bearings, one of said rings B being shown in position upon the crank-shaft in Figs. 1 and 2. The screw-threaded parts a, with which the bearing-ring B is engaged, is located at the extreme end of the shaft proper adjacent to its junction with the crank-arm A². Said crank-shaft is also provided, adjacent to said arm A², with a flange A⁴ for the attachment of a sprocket-wheel C, said flange in the instance shown being arranged in the same plane with the inner side of the adjacent crank-arm and being made continuous with the latter, so that its inner face a² is approximately flush with the said inner side of the crank-arm. The flange A⁴ is provided with a plurality of screw-threaded apertures a³ a³, arranged at intervals around the crank-shaft A'.

The sprocket-wheel C is provided with a flat annular central part or hub C', adapted to rest in contact with the inner face of said flange A⁴, which is provided with a plurality of apertures c c, corresponding to and adapted to register with the apertures a³ of the flange A⁴. Screws C² C² are inserted through the hub C' and threaded into the flange A⁴, whereby said parts are secured together, the heads c' c' of the screws being countersunk into the inner face of the hub, so as to lie flush with the latter, as shown in dotted lines, Fig. 2. The bearing ring or cone B is provided with a flat annular surface, which is arranged to fit closely against the inner face of the hub and to thereby positively prevent the screws C² C² from working loose while the bearing-ring is in position.

In order to connect the sprocket-wheel C with the crank-arm A² at a point radially outside of the hub, so as to afford a driving connection of the sprocket with the crank-axle separate from and in addition to the securing-screws C² C², the hub is provided with a projecting part or arm C³, arranged to extend outward in a plane parallel with the inner side of the crank-arm A², which part is apertured, as at c², and engages a lug A⁵, formed integrally upon the said arm A², in this instance at a point distant from the center of the crank-shaft approximately equal to one-half of the radius of the sprocket-wheel. The

said lug A⁵ is arranged to extend laterally inward or toward the sprocket-wheel parallel with the crank-shaft A', and the apertured part of the arm C³ is arranged to fit accurately thereon, so that when the sprocket-wheel is placed upon the crank-shaft said wheel will be immovably engaged with the lug A⁵.

A main advantage of the construction described is that a positive driving connection is afforded between the crank-arm and sprocket-wheel, while at the same time the construction is such that the crank-arm may be bent, as it often is by accident, without throwing out of line or disturbing the sprocket-wheel, the projecting arm C³ for this purpose being made of such size and strength that it will yield and bend under a strain less than that sufficient to distort the entire wheel. This is a feature of importance, because while it is comparatively easy to straighten the arm should this become bent in the manner described it is practically impossible to restore a sprocket-wheel to its original shape after it has become bent or thrown out of true. Moreover, if the crank-arm be twisted, as often occurs, by the striking of the pedal against the ground or some obstruction the projecting arm C³ may also be twisted or bent without injury to the wheel. In any case repairs can easily be made, because the said arm C³ can be easily bent back to place or straightened when bent, distorted, or twisted through accident to the crank-arm.

In order to afford room for clearance both for the sprocket-chain and the guard therefor between the crank-arm and the rim of the wheel, the latter is made dished, so as to carry the rim away from the said crank-arm, as indicated in Fig. 2. The particular sprocket-wheel herein shown is made of skeleton form, as usual, having a plurality of spokes C⁴ C⁴ made integral with the rim of the hub. When the arm or part C³ is made separate or independent from the spokes, as shown in this instance, the latter, owing to the dished form of the wheel as a whole, will obviously extend out from the hub at an angle with the said part C³, as indicated in said Fig. 2. If desired, however, the part which extends outward from the hub and is engaged with the lug A⁵ may itself constitute one of the spokes, such a construction being illustrated at C⁵, Fig. 4. This latter construction is not so desirable as that shown in the other figures, because bending of the one spoke is more likely to throw the wheel out of true than the bending of a special arm. Nevertheless the construction described produces some of the advantages obtained by the construction shown in the other figures, because it affords a simple and convenient means of giving a direct, rigid, and positive driving connection between the wheel and crank-arm of cheap, simple, and easily-constructed form and one in which accidental bending of the arm is not

liable to throw the wheel out of true, because the one spoke which is engaged by the lug on the crank-arm may be considerably bent before the wheel itself will be bent or distorted as a whole.

Other advantages that may be named are the facility with which the parts may be assembled and the rigid character of the connection formed.

While I have herein shown what I deem to be the preferred embodiments of the invention, yet it will be obvious that the details of construction may be varied to some extent without departure from the invention.

A special advantage is obtained in the use of a sprocket-wheel of dished form having an arm which is located in the same plane with the wheel-hub, for the reason that by this construction the rim of the wheel may be located at a suitable distance from the crank-arm to give room for the chain and chain-guard, while at the same time the part of the wheel which engages the crank-arm may be located close to the same and the lug on the crank-arm may be made short, with obvious advantages with respect to both the strength and appearance of the parts.

I claim as my invention—

1. The combination with a crank-shaft provided with a crank-arm having an integral lug projecting laterally therefrom at a point remote from the shaft, of a sprocket-wheel mounted upon the shaft adjacent to the crank-arm and provided with an arm projecting outwardly from the hub thereof and having its end free or disconnected from other parts of the wheel, said arm terminating at and engaged with said lug, whereby the bending of said arm will have no tendency to distort the wheel-rim.

2. The combination with a crank-shaft provided with a crank-arm having an integral lug projecting laterally therefrom at a point remote from the crank-shaft, of a dished sprocket-wheel mounted on the crank-shaft with its convex side adjacent to the said crank-arm and provided with an arm arranged to project outwardly from the hub thereof in the plane of said hub and which is engaged at its free end with said lug.

3. The combination with a crank-shaft provided with an integral arm, having a lug upon its inner side at a point remote from the crank-shaft, said shaft having also an annular flange integral with the shaft and crank-arm and having its inner face in the same plane with the inner surface of the said crank-arm, and the shaft being provided with a screw-threaded enlargement adjacent to said flange, of a sprocket-wheel having a flat annular hub arranged to rest in contact with said annular flange, and an integral radial arm on the hub engaged with said lug, means for attaching the hub to said flange comprising a plurality of screws or bolts inserted through the hub

and flange and having countersunk heads on the inner surface of the flange, and a bearing-ring engaging said screw-threaded enlargement and bearing against the inner side 5 of the hub and against the said heads of the screws or bolts to hold the same from displacement.

In testimony that I claim the foregoing as

my invention I affix my signature, in presence of two witnesses, this 5th day of February, 1896.

WILLIAM H. FAUBER.
